US00D577581S

(12) **United States Design Patent**
Koza

(10) **Patent No.:** **US D577,581 S**
(45) **Date of Patent:** **** Sep. 30, 2008**

(54) **CORK PACKAGING BLOCK**

(75) Inventor: **Michelle Koza**, Santa Monica, CA (US)

(73) Assignees: **Sony Corporation**, Tokyo (JP); **Sony Electronics Inc.**, Park Ridge, NJ (US)

(**) Term: **14 Years**

(21) Appl. No.: **29/297,791**

(22) Filed: **Nov. 19, 2007**

(51) **LOC (8) Cl.** **09-03**

(52) **U.S. Cl.** **D9/432**

(58) **Field of Classification Search** **D9/430-433,**
